US0D1046017S

(12) **United States Design Patent** (10) **Patent No.:** **US D1,046,017 S**
(45) **Date of Patent:** **** Oct. 8, 2024**

(54) **ELEMENT FOR POSEABLE ACTION FIGURE**

(71) Applicant: **Dong Xu**, Wuxi (CN)

(72) Inventor: **Dong Xu**, Wuxi (CN)

(**) Term: **15 Years**

(21) Appl. No.: **29/937,346**

(22) Filed: **Apr. 15, 2024**

(51) **LOC (14) Cl.** **21-01**

(52) **U.S. Cl.**

USPC **D21/658; D21/578**

(57) **CLAIM**

The ornamental design for an element for poseable action figure, as shown and described.

DESCRIPTION

FIG. 1 is a bottom perspective view of an element for poseable action figure showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings depict portions of the element for poseable action figure that form no part of the claimed design.

1 Claim, 7 Drawing Sheets
